UNITED STATES PATENT OFFICE

123,332

DESIGN FOR A WALLPAPER

Henry H. Allman, Philadelphia, Pa.

Application October 3, 1940, Serial No. 95,607

Term of patent 3½ years

To all whom it may concern:

Be it known that I, Henry H. Allman, a citizen of the United States of America, residing in Philadelphia, county of Philadelphia, and State of Pennsylvania, have invented a new, original, and ornamental Design for a Wallpaper, of which the following is a specification, reference being had to the accompanying drawing, forming part thereof, wherein the figure of the drawing is a plan view of a wallpaper showing my design.

I claim:

The ornamental design for a wallpaper, substantially as shown.

HENRY H. ALLMAN.
